(57) **CLAIM**

The ornamental design for an article of furniture, as shown and described.

DESCRIPTION

FIG. 1 is a perspective view of a first embodiment of an article of furniture showing our new design with a headrest in a lowered state;

FIG. 2 is a plan view thereof with the headrest in a lowered state;

FIG. 3 is a left side view thereof with the headrest in a lowered state, the right side view being a mirror image;

FIG. 4 is a front view thereof with the headrest in a lowered state;

FIG. 5 is a rear view thereof with the headrest in a lowered state;

FIG. 6 is a perspective view of the first embodiment of the article of furniture showing our new design with the headrest in a raised state;

FIG. 7 is a plan view thereof with the headrest in a raised state;

FIG. 8 is a left side view thereof with the headrest in a raised state, the right side view being a mirror image;

FIG. 9 is a front view thereof with the headrest in a raised state;

FIG. 10 is a rear view thereof with the headrest in a raised state;

FIG. 11 is a perspective view of a second embodiment of an article of furniture showing our new design with a headrest in a lowered state;

FIG. 12 is a plan view thereof with the headrest in a lowered state;

FIG. 13 is a left side view thereof with the headrest in a lowered state, the right side view being a mirror image;

FIG. 14 is a front view thereof with the headrest in a lowered state;

FIG. 15 is a rear view thereof with the headrest in a lowered state;

FIG. 16 is a perspective view of the second embodiment of the article of furniture showing our new design with the headrest in a raised state;

FIG. 17 is a plan view thereof with the headrest in a raised state;

FIG. 18 is a left side view thereof with the headrest in a raised state, the right side view being a mirror image;

(Continued)

FIG. 19 is a front view thereof with the headrest in a raised state;
FIG. 20 is a rear view thereof with the headrest in a raised state;
FIG. 21 is a perspective view of a third embodiment of an article of furniture showing our new design with a headrest in a lowered state;
FIG. 22 is a plan view thereof with the headrest in a lowered state;
FIG. 23 is a left side view thereof with the headrest in a lowered state, the right side view being a mirror image;
FIG. 24 is a front view thereof with the headrest in a lowered state;
FIG. 25 is a rear view thereof with the headrest in a lowered state;
FIG. 26 is a perspective view of the third embodiment of the article of furniture showing our new design with the headrest in a raised state;
FIG. 27 is a plan view thereof with the headrest in a raised state;
FIG. 28 is a left side view thereof with the headrest in a raised state, the right side view being a mirror image;
FIG. 29 is a front view thereof with the headrest in a raised state; and,
FIG. 30 is a rear view thereof with the headrest in a raised state.

The broken lines illustrate portions of the article of furniture that form no part of the claimed design.

1 Claim, 6 Drawing Sheets
